[57] CLAIM

The ornamental design for a combined broom head holder and handle attachment, as shown and described.

DESCRIPTION

FIG. 1 is a top, front and left side perspective view of a combined broom head holder and handle attachment showing my new design;

FIG. 2 is a left side elevational view thereof with the right side being a mirror image thereof;

FIG. 3 is a front elevational view thereof;

FIG. 4 is a rear elevational view thereof;

FIG. 5 is a top plan view thereof; and,

FIG. 6 is a bottom view thereof.

The broken lines showing of a broom head and handle are for illustrative purposes only and form no part of the claimed design.

FIG.1
